SLIDE TUNER

Charles E. Lyon, Jr., Des Plaines, Ill., assignor to Motorola, Inc., Chicago, Ill., a corporation of Illinois

Application September 11, 1958, Serial No. 760,325

10 Claims. (Cl. 74—10.37)

This invention relates generally to tuning apparatus for radio receivers, and more particularly to a tuner for automobile radio receivers having a pushbutton operating mechanism which may be readily preset to select predetermined frequencies within a frequency range, and having a continuous operating mechanism for manual tuning throughout the frequency range.

Tuners having pushbuttons for automatic tuning are commonly provided with a mechanism which may be adjusted to set up the predetermined frequencies for automatic selection. Known tuners of this type are somewhat bulky and, therefore, are not ideally suited for use with automobile radios which must be small because of the limited availability of mounting space on the dashboard of present day automobiles. Some known constructions are also difficult to adjust, so that the average listener cannot set up or change the automatic stations conveniently. Constructions which may be set up easily are quite complex and relatively costly.

Accordingly, it is an object of this invention to provide a tuner for automobile radio receivers which is substantially reduced in size and which may be mass produced at low cost.

Another object of the invention is to provide a pushbutton tuner with a simple adjustment mechanism for setting up automatic stations which operates easily and positively and which requires few component parts.

A feature of the invention is the provision of a small and compact tuner for a radio receiver including a plurality of movable key slides having adjustable pins which are located in predetermined control positions with respect to V-shaped cam surfaces on a core carriage, and which are engageable with these cam surfaces upon movement of the respective key slides to move the core carriage to predetermined tuning positions.

Another feature of the invention is the provision of key slides having laterally movable pins for cooperation with the V-shaped cams as described above, and a quick-release locking construction which frees the pins for lateral movement to a new control position and then locks the same by movement of the actuating portion of the slide.

A further feature of the invention is the provision of a tuner as described above including a compact continuous tuning mechanism having a worm screw and a meshing worm gear connected by a friction clutch to the core carriage, so that the worm gear rotates and walks along the worm screw when the carriage is moved by the key slides but remains rotationally fixed and follows the threads of the worm screw to move the core carriage when the worm screw is rotated by a manual tuning shaft.

The invention is illustrated in the accompanying drawings in which:

Fig. 1 is a top view in longitudinal section of a tuner in accordance with the invention;

Fig. 2 is a front view of the tuner of Fig. 1 with the

2

front plate broken away to reveal the internal mechanism;

Fig. 3 is an end view in transverse section of the tuner of Fig. 1;

5 Fig. 4 is a detail view of one of the key slides of the tuner of Figs. 1-3; and

Fig. 5 is a detail view similar to Fig. 4 showing the key slide in the unlocked condition.

In practicing the invention there is provided a tuner 10 having an automatic control mechanism including a longitudinally movable core carriage having a plurality of V-shaped cam surfaces and a plurality of key slides movable laterally with respect to the carriage and each having an adjustable pin which is engageable with one of the cam surfaces to move the carriage to a predetermined tuning position. A continuous control mechanism is provided including a worm screw and a meshing worm gear which is held rotationally fixed by a friction clutch and follows the threads of the worm screw to move the carriage during continuous operation. When the key slides are operated, the friction clutch slips and permits the worm gear to rotate and walk along the worm screw as the core carriage moves, so that it is not necessary to provide parts to uncouple the continuous control during automatic operation. The continuous control mechanism is very compact and cooperates with the automatic control mechanism in a manner which permits a substantial reduction in the size of the tuner. In normal operation the adjustable pins of the key slides are held in place by a quick-release lock mechanism including a locking lever which is forced against the pin by an actuating portion of the key slide. When the actuating portion is pulled out, the locking lever is released, and this frees the pin for lateral movement on the slide. When the key slide is then depressed, the movable pin engages the V-cam and follows its sloping cam surface to the base of the V. Further pressure on the key slide moves the actuating portion relative to the slide and this forces the locking lever against the pin locking it in the new control position.

In Figs. 1, 2 and 3 there is shown a tuner 10 including a channel-shaped core carriage 40 which is movably supported in a frame 11 by the rollers 16 which are guided in slots 17 provided in the back 15 of the frame. The carriage 40 has a back portion 48, two channel portions 47 having V-shaped cam surfaces 41—46 thereon, and an end portion 49 which supports four cores 51 in alignment with four tuning coils 52 contained in a coil housing 53. Part of the housing 53 is broken away in Fig. 1 to give a better view of the core carriage 40. The tuning coils 52 are connected to terminals 54 mounted on the housing 53, and the terminals 54 may be wired into the tuning circuits of a radio receiver. The cores 51 are moved in and out of the coils 52 upon longitudinal movement of the core carriage 40, and the position of the cores with respect to the coils determines the frequency of the radio signals picked up and reproduced by the associated receiver.

The core carriage 40 may be moved to preset tuning positions to select radio signals of predetermined frequencies by operation of an automatic control mechanism including a plurality of key slides 21—26 which are disposed in two rows on the frame 11 and which are actuated to engage the V-cams 41—46 by depressing the pushbuttons 29. The key slides each include a slide portion 27, and a key portion 28 which is normally locked in a fixed position with respect to the slide. The edges of the slide members 27 fit into notches 56 provided in both the front plate 12 and the back portion 15 of the frame 11, and the projecting portions 57 of these edges have shoulders 58 which engage the back of frame 11 when the key slide is fully depressed and other shoulders

59 which engage the front plate 12 to define the initial position of the key slides. Coil springs 61 (Fig. 3) may be attached to the front plate 12 and to the bent-over ear 62 on the slide member 27 to return the key slides to their initial position when they are released.

The key slides 21-26 are respectively provided with pins 31-36 which are engageable with V-shaped cam surfaces 41-46 formed in the channel portions 47 of the core carriage 40. The pins 31-36 are normally locked in place on the key slides by a locking mechanism which will be explained later, but it may be noted at this point that the pins are movable along the slots 37 laterally with respect to the key slides to different control positions. The spacing between the centers of the slots 37 is the same as the spacing between the bases 50 of the V-cams 41-46, so the condition where the centers of slots 37 and the bases 50 are aligned as illustrated is a convenient reference position. The amount the pins are offset from the centers of their guide slots 37 controls the displacement of the carriage 40 from this reference position when any one of the key slides is actuated.

The automatic operation may be understood most clearly from a consideration of Fig. 1. The key slide 21 is shown in the fully depressed position with the pin 31 engaging both sides of the V-cam 41 adjacent the base 50. It may be noted that the base 50 is slightly narrower than the diameter of pin 31 to ensure that the pin engages both sides of the cam surface in the fully depressed position, and this positively locates the core carriage. The position of the cores 51 with respect to the coils 52 controls the inductance value of the tuning circuits of the associated radio receiver and, therefore selects a radio signal of a particular frequency. If it is desired to tune in a signal of another frequency, the key slide 23, for example, may be pushed in. When the pin 33 engages the cam surface 43, the carriage 40 will be moved to the right and the pin 33 will follow the right side of surface 43 as the slide is depressed further until the pin reaches the base 50. The sides of the cam surfaces are slightly curved so that as the pin moves along the side, the direction of the resultant force acting on the carriage varies. The curvature is convex so that as the lateral distance between the pin 33 and the base 50 decreases, less actuating force is required to move the carriage. This controls the "touch" or "feel" of the pushbuttons and helps to make the key slides operate smoothly. The cores 51 move into the coils 52 changing the inductance value in the tuning circuits of the receiver and selecting a new station. The core carriage 40 is held in the selected position by the resistance of the gear train associated with the continuous control mechanism 19 which will be explained later. A dial mechanism 13 including a pointer 63 on a pivotal arm 64 moves across the face of a dial panel 65 to give a visual indication of the station which has been selected. The arm 64 is connected to a support bracket 66 by a pin 67 which is slidable in a slot 68, and its movement is controlled by a link 69 pivotally connected to arm 64 at one end and pivotally connected to the support 66 at the other end.

In order to change the station or radio signal which is set up for selection by any one of the key slides, the pin of the key slide may be moved to a new control position. This operation may be understood by considering Figs. 1, 4 and 5 together. The key slide 23 is shown in detail in Figs. 4 and 5 to illustrate the locking construction which holds the pin 33 in place and which may be quickly released to free the pin for adjustment. It may be seen that both the slide member 27 and the key 28 are plates and that the pin 33 has an enlarged base portion 38 between the plates which is held tightly against the slide 27 adjacent the slot 37 by a locking lever 71. The lever 71 is supported at both ends in openings which are cut out of the bent-over leg

portions 81 and 82 of the slide 27. The opening in leg 82 is large enough to permit pivotal movement of the lever. The lever 71 has a hump 72 which engages another hump 73 in the plate 28 when the key slide is in the locked condition, and the hump portions 72 and 73 apply resilient pressure to the lever 71 so that raised surface 74 is forced firmly against the pin 33 to hold it in place. They key 28 is movable with respect to the slide 27 between the locked position shown in Fig. 4 where the tongue 75 abuts one end of the opening 76, and an unlocked position shown in Fig. 5 where the bent end 78 of key 28 engages leg 82. To unlock the pin 33 the key 28 is pulled out, and the hump 73 in the key 28 slides out from underneath the hump 72 in the locking lever 71. This permits the lever 71 to move away from the pin 33 under pressure applied by the leaf spring 83. The station which is to be set up for selection by the key slide 23 is tuned in by operating the continuous control 19. The key slide 23 is then pushed in, and the pin 33 engages cam surface 43 and is moved along slot 37 as it follows surface 43 to the base 50 of the V-cam. The pin 33 is now positioned to provide automatic selection of the desired station and may be locked in place. This is accomplished by pushing harder on the button 29 so that the key 28 moves with respect to slide 27 to engage the humps 72 and 73 and force lever 71 against the pin 33. It may be noted that during the first portion of the movement of the key slide, the members 27 and 28 move together and not relatively because of the resistance between the humps 72 and 73 and also because of the resistance between the hump 77 and the leg 81. When the key slide 23 is in the fully depressed position, increased force must be applied to overcome these resistances and move the key 28 to the right relative to the slide 27 as illustrated.

The continuous control mechanism, designated generally as 19, will be explained with reference to Figs. 1-3. Rotation of the knob 84 turns the shaft 85 and rotates the crown gear 86 on the end of the shaft. A pinion gear 87 meshes with the crown gear 86 and this rotates the worm screw 91. A worm gear 92 meshes with the worm screw 91 and is affixed to a shaft 93 which also has a disc 94 of ferro-magnetic material affixed thereto. The shaft 93 is rotatably supported by a support arm 97 which has a permanent magnet 96 attached thereto. A friction washer 95 is secured to the magnet and frictionally engages the disc 94. The assembly including disc 94, shaft 93 and gear 92 will rotate only when the force applied to gear 92 is not sufficient to overcome the resistance of the movable parts connected thereto but is sufficient to overcome the frictional resistance of the washer 95 so that disc 94 slips. The magnitude of this frictional resistance is determined by the coefficient of friction between disc 94 and washer 95 and the pull exerted by the magnet 96 on disc 94. When the worm screw 91 is turned during continuous tuning, the worm gear 92 does not rotate because the resistance of the carriage to movement is very slight, so the teeth of gear 92 follow the threads of worm screw 91 and the core carriage 40 moves. When one of the pushbuttons 29 is depressed, the force exerted through the worm gear 92 on the worm screw 91 is not sufficient to turn it, but is sufficient to overcome the frictional force holding gear 93. Therefore, disc 94 slips and gear 93 rotates and walks along the threads of worm screw 91. The support arm 97 is pivotally connected to a bracket 98 which is attached to the core carriage 40, and a spring 99 biases the arm 97 to keep the teeth of gear 92 in full engagement with the threads of screw 91 so that there is no slippage and the core carriage does not drift under vibration.

It is apparent from the foregoing description that the tuner of the invention is very compact and is easily operated. The efficient arrangement of gears and clutch parts in the continuous tuning control mechanism combined with the compact arrangement of the V-cams and key

slides provides a tuner of considerably reduced size as compared with known constructions. The stations for automatic selection may be set up very conveniently by a simple pull-push operation of the key slides which does not require close attention even from the most unskilled operator.

I claim:

1. A tuner for a radio receiver including in combination, a support, a carriage movable linearly on said support, circuit means controlled by said carriage for selecting radio signals of predetermined frequencies within a frequency range upon movement of said carriage to predetermined tuning positions, said carriage having a plurality of V-shaped cam surfaces, a plurality of key slides movable linearly on said support perpendicular to the movement of said carriage, means limiting the movement of said key slides to a predetermined range of movement, said key slides each having a cam member thereon engageable with a corresponding one of said V-shaped cam surfaces to move said carriage to one of the predetermined tuning positions thereof, means on said key slides to permit lateral movement of said cam members with respect to the associated key slides to different tuning control positions, and locking means carried on each of said key slides and engageable with said cam members to lock the same in selected control positions, said key slides each having an actuating member movable with said key slide and relatively movable with respect to said key slide in a direction perpendicular to said carriage to release and re-engage said locking means.

2. A tuner for a radio receiver including in combination, a support, an elongated carriage movable longitudinally on said support and including spaced parallel plates, circuit means controlled by said carriage for selecting radio signals of predetermined frequencies within a frequency range upon movement of said carriage to predetermined tuning positions, a plurality of generally V-shaped cam surfaces on said plates of said carriage, each of said cam surfaces having predetermined curvature, a plurality of key slides disposed in parallel rows on said support and movable linearly in a direction perpendicular to the movement of said carriage, said key slides each having a laterally adjustable cam member thereon engageable with a corresponding one of said V-shaped cam surfaces to move said carriage to one of the predetermined tuning positions thereof, with the curvature of said cam surfaces controlling the pressure required to depress said key slides and move said carriage.

3. A tuner for a radio receiver including in combination, a support, a carriage movable linearly on said support, circuit means controlled by said carriage for selecting radio signals of predetermined frequencies within a frequency range upon movement of said carriage to predetermined tuning positions, a plurality of V-shaped cams on said carriage, a plurality of key slides movable linearly on said support in a direction perpendicular to the movement of said carriage, said key slides each having a laterally adjustable cam member thereon engageable with a corresponding one of said V-shaped cams to move said carriage to one of the predetermined tuning positions thereof, said V-shaped cams having sides of predetermined curvature for controlling the effective force transmitted to said carriage according to the lateral position of said cam members with respect to said V-shaped cams upon engagement therewith.

4. A tuner for a radio receiver including in combination, a support, a carriage movable linearly on said support, circuit means controlled by said carriage for selecting radio signals of predetermined frequencies within a frequency range upon movement of said carriage to predetermined tuning positions, a plurality of V-shaped cam surfaces on said carriage, a plurality of key slides movable linearly on said support in a direction perpendicular to the movement of said carriage, said key slides each

having an actuating portion and an adjustable cam member engageable with one of said V-shaped cam surfaces to move said carriage to one of the predetermined tuning positions thereof, said adjustable cam members each being laterally movable on said key slides to various control positions having a predetermined relation to the V-shaped cam surface associated therewith for controlling the tuning positions to which said carriage is moved upon actuation of said key slides, said key slides each having quick-release lock means engaging and holding said adjustable cam members in selected control positions, said lock means being released upon predetermined movement of said actuating portion away from said carriage and re-engaged upon predetermined movement of said actuating portion toward said carriage.

5. A tuner for a radio receiver including in combination, a support, a carriage movable linearly on said support, circuit means controlled by said carriage for selecting radio signals of predetermined frequencies within a frequency range upon movement of said carriage to predetermined tuning positions, a plurality of V-shaped cam surfaces on said carriage each having sides of predetermined curvature, a plurality of key slides movable linearly on said support perpendicular to the movement of said carriage, said key slides each having an actuating portion and an adjustable pin engageable with one of said cam surfaces to move said carriage to one of the predetermined tuning positions thereof, said adjustable pins each being movable laterally on said key slides to various control positions having a predetermined relation to the cam surface associated therewith for controlling the tuning positions to which said carriage is moved upon actuation of said key slides, said key slides each having quick-release lock means for engaging and holding said adjustable pins in selected control positions, said lock means being held against said pin by said actuating portion, and said lock means releasing said pin upon predetermined movement of said actuating portion away from said carriage and re-engaging said pin upon predetermined movement of said actuating portion toward said carriage.

6. A tuner for use with a radio receiver to select radio signals of predetermined frequencies within a frequency range, including in combination, a support, a carriage movable linearly on said support through a range of movement, circuit means controlled by said carriage according to the movement thereof for controlling the tuning of the radio receiver, a plurality of V-shaped cam surfaces on said carriage, a plurality of key slides movable linearly on said support perpendicular to the movement of said carriage, said key slides each having an adjustable member thereon engageable with one of said V-shaped cam surfaces to move said carriage to a predetermined tuning position, said adjustable members each being laterally movable with respect to said key slides, quick-release lock means for holding each of said adjustable members in a selected position and for releasing the same for adjustment, each of said adjustable members when in the released condition being moved laterally by the associated V-shaped cam surface upon engagement therewith and riding said cam surface to a control position aligned with the base thereof upon depressing the associated key slide, said lock means being operable upon further depression of said key slide to hold said adjustable member in said control position for setting a corresponding tuning position for said carriage.

7. A tuner for a radio receiver including in combination, a support, a carriage movable linearly on said support, circuit means controlled by said carriage for selecting radio signals of predetermined frequencies within a frequency range upon movement of said carriage to predetermined tuning positions, a plurality of V-shaped cam surfaces on said carriage, a plurality of key slides movable linearly on said support perpendicular to the movement of said carriage, said key slides each having a later-

ally movable pin thereon engageable with one of said cam surfaces to move said carriage to one of the predetermined tuning positions thereof, quick-release lock means for holding each of said pins in a selected position and for releasing the same for adjustment, said lock means including a lever supported on each of said key slides and engageable with the pin thereof, each of said key slides including an actuating portion movable relative to the remainder of said key slide to engage and release said lever and said pin and applying pressure thereto for locking said pin, each of said pins when in the released condition being moved laterally by the associated V-shaped cam surface upon engagement therewith and riding said cam surface to a control position aligned with the base thereof for controlling the tuning positions to which said carriage is moved upon actuation of said key slides.

8. A tuner for a radio receiver including in combination, a support, a carriage movable linearly on said support, circuit means controlled by said carriage for selecting radio signals of predetermined frequencies within a frequency range upon movement of said carriage to predetermined tuning positions, a plurality of V-shaped cam surfaces on said carriage, a plurality of key slides movable linearly on said support perpendicular to the movement of said carriage, said key slides each having an adjustable pin thereon engageable with one of said cam surfaces to move said carriage to one of the predetermined tuning positions thereof, said key slides including a slidable plate having an elongated slot therein receiving and guiding said pin, a lock plate movable between first and second positions with respect to said slide plate and having an actuating portion thereon, and a lever supported on said slide plate and engageable with said pin to hold the same against said slide plate, said lock plate including a resilient portion engaging and applying resilient pressure to said lever in said first position for locking said pin and releasing said lever in said second position for permitting movement of said lever to release said pin, said adjustable pins when in the released condition being movable in said slots to various control positions having a predetermined relation to the V-shaped cam surface associated therewith for controlling the tuning positions to which said carriage is moved upon actuation of said key slides.

9. A tuner for use with a radio receiver including in combination, a support, a carriage movable linearly on said support through a range of movement, circuit means controlled by the movement of said carriage for selecting radio signals within a range of frequencies, a plurality of V-shaped cam surfaces on said carriage, a plurality of movable members each having a portion engageable with one of said V-shaped cam surfaces upon movement of said movable member for moving said carriage to pre-determined tuning positions, continuous control means coupled to said carriage for moving the same through

the range of movement thereof, said continuous control means including a worm screw and a meshing worm gear, friction clutch means coupling said worm gear to said carriage, and driving means for rotating said worm screw, said clutch means including a magnet, and a magnetic member coupled to said worm gear, with friction material between said magnet and said magnetic member frictionally holding said magnetic member and said worm gear so that the meshing teeth thereof follow the threads of said worm screw for moving said carriage upon actuation of said driving means, and said carriage moving in response to actuation of said movable members and applying force to said magnetic member causing the same to slip so that said worm gear rotates and walks along said worm screw absorbing said force without transmitting the same.

10. A tuner for use with a radio receiver including in combination, a support, a carriage movable linearly on said support through a range of movement, circuit means controlled by the movement of said carriage for selecting radio signals within a range of frequencies, a plurality of movable members each engageable with one of said V-shaped cam surfaces for moving said carriage to predetermined tuning positions, continuous control means coupled to said carriage for moving the same through the range of movement thereof, said continuous control means including a worm screw, a worm gear meshing with said worm screw and having a rotary shaft affixed thereto, friction clutch means coupling said worm gear to said carriage, said clutch means including a support arm pivotally connected to said carriage and supporting said shaft, a magnetic disc affixed to said shaft, a permanent magnet affixed to said support arm and attracting said magnetic disc, and friction material interposed between said disc and said magnet and engaging said disc for resisting rotation of said shaft and said gear, means biasing said pivotal support arm for maintaining said worm gear in full tooth engagement with said worm screw, and driving means for rotating said worm screw, said magnetic disc being held by said friction material and said magnet to prevent rotation of said worm gear upon actuation of said driving means so that the teeth of said worm gear follow the threads of said worm screw and apply force through said shaft to move said carriage, and said carriage moving in response to actuation of said movable members and applying force to said shaft thereby causing said magnetic disc to rotate and slip on said friction material so that said worm gear rotates and walks along said worm screw absorbing said force without transmitting the same.
